UNITED STATES PATENT OFFICE

128,825

DESIGN FOR A VEHICLE BODY

Ellen Willett Magill, Chicago, Ill.

Application December 7, 1940, Serial No. 97,147

Term of patent 7 years

To all whom it may concern:

Be it known that I, Ellen Willett Magill, a citizen of the United States, residing at Chicago, in the county of Cook and State of Illinois, have invented a new, original and ornamental Design for a Vehicle Body, of which the following is a specification, reference being had to the accompanying drawings, forming a part thereof.

In the said drawings—

I claim:

The ornamental design for a vehicle body, as shown.

ELLEN WILLETT MAGILL.
